UNITED STATES PATENT OFFICE

128,304

DESIGN FOR A FORK OR ANALOGOUS ARTICLE

Harold E. Nock, Newburyport, Mass., assignor to
Towle Manufacturing Company, Newburyport,
Mass., a corporation of Massachusetts

Application March 21, 1941, Serial No. 99,753

Term of patent 14 years

To all whom it may concern:

Be it known that I, Harold E. Nock, a citizen of the United States, residing at Newburyport, in the county of Essex and Commonwealth of Massachusetts, have invented a new, original, and ornamental Design for a Fork or Analogous Article, of which the following is a specification, reference being had to the accompanying drawing, forming a part thereof.

In the accompanying drawing,

Figure 1 is a front elevational view of a fork showing my new design;

Figures 2 and 3 are sectional views on the lines 2—2 and 3—3, respectively, of Figure 1; and

Figure 4 is an edge elevational view of the fork. The essential features of my design reside in the parts shown in full lines.

The design is illustrated as embodied in the handle of a fork, but the design may also be embodied in or applied to other handles of like nature.

I claim:

The ornamental design for a fork or analogous article, substantially as shown and described.

HAROLD E. NOCK.
